UNITED STATES PATENT OFFICE.

WILHELM GINTL, OF AUSSEGG, AUSTRIA-HUNGARY.

APPARATUS FOR THE CONTINUOUS ELECTROLYSIS OF ALKALI CHLORIDS.

SPECIFICATION forming part of Letters Patent No. 690,865, dated December 31, 1901.

Application filed October 10, 1900. Serial No. 32,598. (No model.)

To all whom it may concern:

Be it known that I, WILHELM GINTL, of Aussegg-on-the-Elbe, Bohemia, Austria-Hungary, have invented certain new and useful 5 Improvements in Apparatus for the Continuous Electrolysis of Alkali Chlorids and the Like, of which the following is a specification, with drawings.

The object of the invention is to produce 10 an improved apparatus of this character that shall be simple and economical in construction and operation and shall be durable and be so highly efficient in action as to utilize the current to nearly the theoretical limit 15 and to produce strongly alkaline cathode liquors.

This apparatus includes a number of bells 20 or gas-holding cells open at the bottom, but closed gas-tight at the top. Within these are 25 placed horizontal anodes, while without are carried the cathodes. The bells dip into a comparatively shallow cell or vat provided with an outlet for the cathode liquor. Fresh 30 electrolyte solution is introduced into each bell through a supply device or pipe above each anode. The size of the anode is such as to leave but narrow intervals or channels between it and the wall of the bell for the 35 passage of the electrolyte to the space below the anode. Bubbles of chlorin gas rising through these channels effect an intimate mixture of the liquids.

The accompanying drawings show one preferred construction.

35 Figures 1, 2, 3, and 4 are respectively a vertical central longitudinal section, a transverse central section, a side elevation, and a plan view of an individual bell. Figs. 5, 6, and 7 are a vertical section on the plane 55 through 40 the vat, showing the rest of the apparatus in full, a vertical section of the same corresponding to Fig. 1, and a plan view of a complete bath apparatus.

Each bell preferably consists of an inverted 45 sheet-iron box *e*, narrow in proportion to its length, open at the bottom and closed above, and coated or lined inside with a layer of non-conducting refractory material which should be impervious to the liquors—*e. g.*, glass, 50 slate, or cement. This layer or lining extends somewhat beneath the lower edge of the box *e*. The anode is a carbon bar or rod *a* of a

size that leaves but a small interval between its sides and ends and the walls of the bell—for example, a few millimeters. The anode 55 is preferably provided with an integral carbon upright *b*, sealed in an aperture in the bell and coated with insulating material—*e. g.*, paraffin or cement—to prevent any formation of chlorin on its surface. The current 60 is supplied through this upright *b*. This vertical carbon *b* is provided with a central perforation *c* and two lateral distributing-pipes *d*, of insulating material—*e. g.*, glass or hard-rubber composition—through which the 65 fresh electrolyte liquor enters. The upper surfaces of the pipes *d* are perforated to insure an equal and gentle distribution of the liquor. Each box *e* may itself serve, as far as it dips 70 into the liquid, for a cathode. Openings *g* or *f* in the top of each bell permit the eduction of the chlorin gas generated. As shown in Fig. 7, only one bell of each bath needs to be provided with an opening *f* for leading the chlorin to its ultimate destination if the openings 75 *g* of the several cells are so connected that the chlorin may pass freely from bell to bell. As shown in Figs. 5, 6, and 7, many of these 80 bells or cells are placed in a single vat or tank *h*, made of insulating refractory material—*e. g.*, slate or glass or coated with such. Care should be taken to leave under and on the sides of the several bells sufficient space for the collection and flow of the alkaline lye. The outlet or overflow-pipe for all the bells 85 belonging to the same bath is placed at a sufficient height to maintain the level of the anode liquor, which is in direct communications with the outer lye, several centimeters above the pipes that distribute the fresh electrolyte. By admitting the fresh solution 90 above the anode and gently and equally distributing it, thereby forcing it to pass through the narrow intervals or spaces around the anodes, continually meeting the rising chlorin 95 bubbles, it is intimately mixed with the anode liquor. In this way a constant uniform composition of the liquid at the anodes is attained, and it cannot grow so weak by the free downflow of the fresh solution as to lead 100 to the electrolysis of water. As there is a considerable interval or space as measured vertically between the bottom of each anode and the lower edge of the bell, the chlorinated

anode liquor lies above but not in immediate contact with the strong alkaline cathode lye. In this space within each bell the conditions are produced for the formation of strata of continually-decreasing alkalinity and specific weight from the bottom upward to the anode. Thus it will be seen that the chlorinated anode liquor, which extends somewhat below the anode, is in contact with a layer extremely poor in free alkali. If the fresh brine or electrolyte be introduced at a rate corresponding to that at which the current decomposes and separates it, the apparatus will then operate under the following conditions: The fresh electrolyte will lie above and around the anode and through it will pass the ascending chlorin gas. It will flow gently down through the restricted spaces around the anodes at the same rate at which it is decomposed, so that when the normal conditions are established there will be no accumulation of salt or of chlorin gas in the space below the anodes and, on the other hand, no accumulation of the alkaline hydrate in the vicinity of the anodes. The alkaline liquor will be drawn off as it is formed and the passage or migration of the alkali ions to the cathodes will be just equal to the rate at which salt is electrolyzed. These conditions are maintained uniformly, the alkalinity of the liquor increasing continuously downward beneath the anodes and the fresh supply of electrolyte not being allowed to pour freely down beneath the anodes and so stir up and destroy the stratification. Of course the anodes may be formed of more than one rod and may touch the walls of the bell at each end or otherwise, leaving a narrow passage between them. They may be made of perforated material, as shown in Fig. 1, and afford only by this means a sufficient passage-way for the electrolyte. The supply-pipe *d* need not of course be connected through the shank or upright *b*, although this is advantageous. The following are claimed as the novel characteristics of the invention:

1. In apparatus for the electrolysis of alkali chlorids and like uses, of the type having means for holding the liquids present, a cath-

ode and a gas-collecting chamber containing an anode, the cathode being outside of the said chamber, the improvement which consists in the anode being supported and proportioned to approximately fit the said chamber horizontally to separate and divide the space above the anode from the space beneath it, and in the means of communication or circulation from above to below the anode being restricted, thereby preventing substantially free circulation, and means for introducing electrolyte into the space above the anode.

2. In apparatus for the electrolysis of alkali chlorids and like uses, of the type having means for holding the liquids present, a cathode and a gas-collecting chamber containing an anode, the improvement which consists in the anode being supported and proportioned to approximately fit the said chamber horizontally and to separate and divide the space above the anode from the space beneath it, the passages or means of circulation from above to below the anode being restricted to prevent free or rapid circulation, and a distributing supply device delivering the inflowing electrolyte gently downward upon the anode, whereby stratification of the electrolytic liquids may be undisturbed, substantially for the purposes set forth.

3. In apparatus for the electrolysis of alkali chlorids and like uses, of the type having means for holding the liquids present, a cathode and a gas-collecting chamber containing an anode, the improvement which consists in the anode being supported and proportioned to approximately fit the said chamber horizontally and to separate and divide the space above the anode from the space beneath it, and a distributing supply device constructed and arranged to deliver the electrolyte into the space above the anode gently over a large area of the anode, substantially as set forth.

Signed this 18th day of September, 1900, at Prague, Austria-Hungary.

WILHELM GINTL.
